UNITED STATES PATENT OFFICE.

CARL J. FREESE, OF ELYRIA, OHIO.

BAG.

1,400,355.

Specification of Letters Patent.

Patented Dec. 13, 1921.

Application filed January 8, 1920. Serial No. 350,067.

To all whom it may concern:

Be it known that I, CARL J. FREESE, a citizen of the United States, and a resident of Elyria, county of Lorain, and State of Ohio, 5 have invented a new and Improved Bag, of which the following is a full, clear, and exact description.

The present invention relates to bags and has reference more particularly to a bag 10 which is produced preferably from cheap material and which includes a closing flap with a handle associated with the flap for carrying the bag.

The primary object of the invention is to 15 improve the construction of bags of this character, especially the means for fastening or anchoring the handle.

For the purpose of illustrating the manner 20 of reducing the invention to practice will be referred to with reference to the accompanying drawing in which,

Figure 1 is a side elevation of one form of bag as proposed by the invention.

Fig. 2 is a sectional view on the line 2—2 25 of Fig. 1.

Fig. 3 is a view in side elevation of a second embodiment of the invention showing the closing flaps as employed in this form in dotted lines as open.

Fig. 4 is a perspective view of one form of 30 handle fastening means with a hanger associated therewith, and

Fig. 5 is another perspective view of the handle fastening means.

Referring now to the drawings in detail and especially concerning Figs. 1 and 2, the bag 35 is preferably made of paper with a closed end 6, and with the sides converging toward and terminating in an open top with one of the sides made to form a closing flap 7 and adapted to overlie the opposite side as shown. The usual string fastening means 8 is adapted to maintain the flap closure closed as is customary in devices of this kind.

Arranged beneath the closure flap 7 is a 45 handle fastening or anchoring means 9 which preferably comprises a relatively stiff strip folded upon itself with its folded edge made to coincide with and bear against the fold of

50 the closing flap 7. Arranged at spaced points preferably on the folded edge of the strip 9 are perforations which are made to receive a flexible handle 10 which may be constructed of cord or the like, and according to the embodiment in Figs. 1 and 2 the

ends of the handle after being passed through the perforations terminate in knots 11 which lie beneath the folds of the strip and are of a size to prevent withdrawal through the perforations. 60

In the construction of handle employed with that embodiment of the invention illustrated in Fig. 3 it is somewhat different from that just mentioned, as instead of knotting the ends of the handle the same is passed 65 through the perforations and along the strip beneath its folded edge to provide a loop. The stiffening strip 9 is the same in both forms but where the handle is shown in Fig. 4 as made in the form of a loop, a suitable 70 coat hanger or the like 12 may be used and suspended from the loop of the hanger beneath the folded sides of the strip and presented in the bag so as to receive the coat or other garment which may be contained in 75 the bag.

The construction of bag shown in Fig. 3 instead of employing the closed end 6, etc., represents a folded structure which may be constructed from a blank and cut with relatively large foldable side flaps 13 which are adapted to be first folded over the body of the bag with their overlapping edges made fast by the string fastening means 14, and with a relatively large end flap 15 which is 85 adapted to be folded to overlie the side flaps 13 and with the closure flap 16 adapted to be folded upon the flap 15 and overlapping the edge thereof, and made fast by the string fastening means 17. In both forms of bag 90 the fastening means for the handle 10 is presented beneath the closure flaps 7 and 16, with the handle 10 passed through the flaps and presented as a hand grip for carrying the bag. 95

It is to be noted that the folded strip 9 aside from its utility as an anchoring or fastening means for the handle also offers a stiffening or reinforcing means for the bag, the advantages of which are best realized when the strip is made as substantially shown and described, that is to say folded to provide a double thickness with the perforations which receive the handle made on the folded edge, whereupon this edge may coincide to the fold in the closure flaps 7 and 16. 100

When a hanger such as 12 is used with the bag the same will offer a convenient means of delivering garments and in this connection it will be appreciated that the handle 110

2
10 aside from providing means for carrying the bag will also offer a means for supporting the bag from a hook with the garment contained therein supported by the 5 hanger.

It will be further understood that the perforations in the folded strip 9 may be reinforced by small paper or metal washers.

Having thus described my invention what 10 I claim as new and desire to secure by Letters Patent is as follows:—

1. A bag having a closure flap provided with spaced openings intermediate of its ends and in the fold thereof, an inverted V-shaped stiff strip arranged beneath the flap and having at the junction of its members openings registering with the openings of the flap, and a cord secured in the openings of the stiff strip and passed through the 20 openings of the flap to form a handle.

2. A bag having a closure flap provided with spaced openings intermediate of its ends and in the fold thereof, an inverted V-shaped stiffening strip arranged beneath the flap and having at the junction of its members openings registering with the openings of the flap, and a cord secured in the openings of the flap and the stiffening strip to form two loops, one lying on the inner 25 face of the stiffening strip at the junction of its members and forming a suspension

means and the other projecting from the edge of the bag and forming a handle.

3. A bag having foldable side flaps, an end flap foldable on the side flaps, and a 35 closing flap foldable upon the end flap, the closing flap having spaced openings in the fold thereof, and provided on its inner face with a stiffening strip having openings registering with the openings of said flap, a 40 cord secured in the openings of the flap and stiffening strip to form two loops, one lying on the inner face of the said strip and forming a suspension means and the other projecting from the edge of the bag and forming a handle, and detachable fastening means for the several flaps.

4. A bag having a closure flap, a stiffening strip arranged beneath said flap, said strip being scored intermediately of its longitudinal edges and folded in inverted V-shaped formation for arrangement beneath the flap, said bag being provided with openings at the fold of the flap and at a considerably spaced distance from the ends thereof, and said strip having similar perforations alining with the perforations of the fold, and a continuous handle looped through the openings and extending between the same beneath the fold of the strip.
